CONDIMENT DISPENSER WITH DISCHARGE OPENINGS THROUGH THE UPPER RIM OF A CONTAINER AND COVERED BY A LID PORTION

Harrison M. Von Duyke, Wilmington, Del., assignor to Von Evan, Inc., Avondale, Pa., a corporation of Delaware

Application December 5, 1946, Serial No. 714,300

3 Claims. (Cl. 222—142.4)

1

This invention relates to condiment dispensers, and it relates more particularly to dispensers designed for the ready and convenient use of salt, pepper, and the like at a dining table.

One of the principal difficulties heretofore encountered in the use of condiment dispensers, particularly those used for discharging common table salt, was due to the natural tendency of the salt to absorb moisture from the air, and to then accumulate in and around the discharge openings so that the same quickly became clogged and the dispenser became inoperative.

In the use of dispensers of the ordinary type, having a plurality of holes for the discharge of the contents, when the holes become clogged or stopped up, they are difficult to clean, and persons attempting to use the same usually become greatly exasperated.

The principal object of the present invention is to provide a dispenser for table condiments, such as salt and pepper, of novel construction and arrangements, so that in the event the discharge openings become clogged, the same may be quickly cleaned and the device put in condition for use with a minimum of effort.

A further object of the invention is to provide a device of the character aforesaid, in which the tendency of the discharge openings to become clogged, will be reduced to a minimum.

A further object of the invention is to provide, as a specific form of device, a unitary container having a plurality of compartments from either of which the material contained therein may be dispensed without the material from the other compartment being discharged at the same time.

The nature and characteristic features of the invention will be more readily understood from the following description, taken in connection with the accompanying drawing forming part hereof, in which:

Figure 1 is a front elevation of a combined salt and pepper shaker embodying the main features of the present invention;

Fig. 2 is a side elevation thereof;

Fig. 3 is a vertical central section thereof taken on the line 3—3 of Fig. 2;

Fig. 4 is a perspective view of the upper portion of the device shown in the previous views but with the lid removed; and

Fig. 5 is a side elevation of the upper portion of a modified form of the device.

It should, of course, be understood that the description and drawing herein are illustrative merely, and that various modifications and

2

changes may be made in the structure disclosed without departing from the spirit of the invention.

Referring now more particularly to Figs. 1, 2, 3 and 4 of the drawing, the invention as there shown comprises a suitably shaped container 6 having a central vertically disposed partition 7, so as to provide two interior compartments 8 and 9, designed to hold salt and pepper respectively.

The openings for the discharge of the contents of the compartments 8 and 9 are made by the provision, in the outer side wall of each compartment, at the top marginal edge thereof, of a series of serrations or indentations 10.

A lid member 11 is provided, having a flat under-surface, the marginal portion of which engages the top edges of the walls of the container 6 and serves, in conjunction with the serrations 10, to provide at each side, at the top, a plurality of openings for the discharge of the material from within the compartments 8 and 9 respectively.

The lid 11 may be attached to the container 6 in any suitable manner, but preferably is designed to be mounted on the top of the container 6 in such manner as to be easily and readily removable therefrom. For example, on each side of the container 6, there may be provided lugs 12 which may be engaged by suitable spring tongues 13 extending downwardly from the side edges of the lid 11. The lid 11 may also be provided with downwardly extending lugs 14, on each side thereof, and disposed toward the ends for the purpose of properly positioning the lid 11 on the top of the container 6.

The operation of the device as above described will be readily understood. When it is desired to discharge the contents of either of the compartments 8 or 9, the container 6 is tilted with the desired serrated side portion disposed downwardly, thereby to cause the material in the lower compartment to be discharged through the apertures 10, the discharge being assisted, if necessary, by shaking the device.

If it should be found that the material does not flow or discharge properly, by reason of the openings 10 being closed by accumulations of the material which should normally pass therethrough, the same may be quickly cleared by removing the lid 11 which, in many instances, will cause the material which has accumulated in the serrated portion 12 to remove itself therefrom. However, if necessary, the serrated portion 12 may be cleaned with any suitable imple-

ment, such as a knife, fork, or any other table utensil which may be convenient. Also, if the material within one of the compartments should become caked or hardened, it will be comparatively easy to break up and pulverized the same, upon the removal of the lid 11, by means of any available table utensil.

In Fig. 5 of the drawing there is shown a modified form of the invention in which, instead of a plurality of indentations or serrations being provided for the discharge of the material, a relatively narrow slot 10a is provided for the discharge of the material within the container.

This slot 10a is provided by cutting out a shallow indentation in the top edge of the end wall of the container, so that when the lid 11 is placed thereon the inner surface of the lid will define one edge of the slot. An arrangement such as this may be even more readily cleaned than is the case with serrated device shown in Figs. 1 to 4, although in some other respects it may not be so desirable.

I claim:

1. A condiment dispenser comprising a container the top marginal edge of which is provided with an indentation extending entirely through the side wall of the container, a lid removably but non-rotatably mounted on said container having portions engaging the top marginal edge of the container and over the indentation providing in connection therewith when the lid is normally positioned on the top of the container, an opening for the sidewise discharge of the material from within the container, and spring means for normally holding the lid on the top of the container, said holding means permitting the lid to be readily removed for the purpose of clearing the discharge opening of any of the material which may lodge therein.

2. A condiment dispenser comprising a container the top marginal edge of which is provided with a serrated portion, the serrations extending entirely through the side wall of the container, a lid removably but non-rotatably mounted on said container having portions engaging the top marginal edge of the container and over the serrated portion of the edge of the container providing in connection therewith, when the lid is normally positioned on the top of the container, a plurality of openings for the sidewise discharge of the material from within the container, and spring means for normally holding the lid on the top of the container, said holding means permitting the lid to be readily removed

for the purpose of clearing the discharge openings of any of the material which may lodge therein.

3. A condiment dispenser comprising a container having a vertical partition subdividing the interior thereof into two compartments, the top marginal edge of said container being provided on each side thereof opposite the central partition with a series of indentations extending entirely through the side wall of the container, a lid removably but non-rotatably mounted in fixed position on said container having portions engaging the top marginal edge of the container and over the aforesaid indentations providing in connection therewith, when the lid is normally positioned on the top of the container, a series of openings on each side for the selective sidewise discharge of the material from the respective compartments, and spring means for normally holding the lid on the top of the container comprising integral tongues depending from the lid and engaging portions of the container at places intermediate the discharge openings, said holding means permitting the lid to be readily removed for the purpose of clearing the discharge openings of any of the material which may lodge therein.
